United States Patent Office.

JOHN H. BELLAMY, OF CHARLESTOWN, MASSACHUSETTS.

Design No. 4,249, dated July 19, 1870.

DESIGN FOR A HAND-GLASS FRAME.

The Schedule referred to in these Letters Patent and making part of the same.

To all whom it may concern :

Be it known that I, JOHN H. BELLAMY, of the city of Charlestown, in the county of Middlesex and State of Massachusetts, have originated and designed a new pattern for Hand Glass, of which the following is a full, clear, and exact description, reference being had to the accompanying photographs making a part of this specification.

This design for a hand-glass represents above the space or glass A, a crown, B, together with cross-keys C C, the crown being surmounted by a globe, D, on the top of which is a cross, E. On the right of glass or space A is a crook, F, and on the left of space A is a miter, G. Below the space or glass A is an open book, H, together with a cross, I, the whole being inclosed in ornamental scroll work.

What I claim as my invention, and desire to secure by Letters Patent, is—

The design or pattern for hand glass herein set forth.

JOHN H. BELLAMY.
